UNITED STATES PATENT OFFICE.

AUGUSTIN SERRA, OF ESSOMES-SUR-MARNE, FRANCE.

WARP-KNITTING MACHINE.

Original application filed December 5, 1923, Serial No. 678,787. Divided and this application filed January 11, 1924. Serial No. 685,643.

To all whom it may concern:

Be it known that I, AUGUSTIN SERRA, a French subject, of Essomes - sur - Marne, Aisne, France, manufacturer, have invented 5 certain new and useful Improvements in Warp-Knitting Machines, of which the following is a specification.

This invention relates to a warp knitting machine for the manufacture of an improved knitted fabric, comprising two sets 10 of threads in which each individual thread is formed into a series of closed loops, each node is formed by the intermeshing of a plurality of loops of separate threads, and the threads are all pulled tight at the nodes. One such fabric, which is semi-transparent, 15 unladderable, and slightly elastic longitudinally, and highly elastic transversely, is described and claimed in my co-pending patent application No. 678,787, of which this is a division. The present invention is also a continuation in part of my copending application for Letters Patent of the U. S. for improvements in method and means 20 for the manufacture of knitted fabrics, filed Dec. 11, 1922, Serial No. 606,223.

The tightening of the threads at the nodes is obtained by causing the fabric to be pulled 25 on the needles, contrary to the usual practice with warp knitting machines, in which the fabric is always loosely suspended. To obtain a high degree of transparency, the length of thread fed per stitch is made greater than usual; this is obtained by giving 30 the guide wires a greater vertical movement than that required merely to pass the threads over the needles. Otherwise, the machine works in the usual manner; the two sets of parallel threads are threaded 35 through the eyes of the guide wires fixed to two carriers, the two carriers being moved up and down simultaneously, but are "shogged" off oppositely in the direction of the width of the fabric, in a manner well 40 known in warp knitting machines.

I append drawings illustrating my invention by way of example, as applied to a rectilinear knitting machine.

Fig. 1 is a diagrammatic view, on an enlarged scale, of one of the fabrics made by a machine according to the present invention.

Figs. 2 to 6 are diagrammatic views in side elevation, showing a cycle of relative 55 positions of the threads, needles, sinkers,

guide wires and pressers at five different instants during the formation of a row of stitches.

Figs. 7 to 11 are diagrammatic views in front of the needles corresponding to Figs. 60 2 to 6.

Fig. 12 is a partial cross section of the machine, showing the actuating device of the presser, and the device for effecting the up-and-down movement of the plates which 65 hold the two sets of guide wires.

Fig. 13 is a similar view showing the needle holder plates, the actuating devices for the guide wires and sinkers, and the rollers 70 from which the threads are unwound and the roller on which the fabric is wound.

Fig. 14 is a front view of the cam shaft which effects the different movements of the machine.

Fig. 15 is a front view, and

Fig. 16 is a side view to a larger scale of the adjustable cam which effects the lateral to-and-fro movements of the guide wire carriers.

Fig. 17 is a perspective view illustrating 80 diagrammatically the Dawson wheel and other mechanism which produces the lateral to-and-fro movements of the guide wire carriers.

Referring to Fig. 1, the threads marked by the odd numbers, 1, 3, 5, are threaded through the eyes of one set of guide wires or yarn guides J, fixed to the carrier j. Those marked by the even numbers, 2, 4, 6, are threaded through the eyes of the other set of guide wires or yarn guides K fixed to the carrier k. Following one of the threads, say that marked 3, it is seen that it is formed into a series of closed loops. At the node A it intermeshes with the threads 1, 2, and 4; at the node B it intermeshes with the threads 1, 2, and 4; at the node C it intermeshes with the threads 4, 5, and 6; at the node D it intermeshes with the threads 4, 5 and 6. Thus the thread 3 intermeshes directly with the five threads 1, 2, 4, 5 and 6. The full course of the thread 3 throughout the fabric is made up of repetitions of the element between the nodes B and E, the node E being exactly similar to the node B. The nodes or stitches are all pulled together tightly as described hereinafter, thus ensuring that in the event of a thread breaking at any point, its ends are held tightly 100 105 110

by five other threads, so that laddering is effectively prevented. In order to show clearly the intermeshing of the various threads, the tightening at the nodes is not shown in the drawing. Between the nodes, the fabric may be made of open texture as shown, so that transparency may be given as desired.

Referring now to Figs. 2 to 11, *w* designates the needle carriers, in which are fixed the needles *W*. The needle carriers are fixed and bolted to the frame of the machine. In Figs. 2 and 7, the sinker carriers *u v*, to which are fixed the sinkers *x*, are at a certain distance from the frame, the presser 19 is raised clear of the needles, and the guide wires are at their lowest position.

After a fraction of a turn of the motor shaft, the members are in the position shown in Figs. 3 and 8. The sinker carriers *u v* and the presser have not moved from their positions as shown in Fig. 2, but the guide wires are raised. At the position of Figs. 3 and 8, the guide wires have been 25 "shogged," that is, moved transversely by means of the arrangement shown in Fig. 17, which is described hereinafter. Relatively to the observer in Fig. 3, *J* has approached and *K* receded, for a distance corresponding 30 to the space between two consecutive needles *W*, or (which amounts to the same thing) between two sinkers *x*, since one needle is placed between each sinker.

The movement continuing, the sinker carriers *u v* draws slightly nearer to the frame of the machine, and the guide wires descend, bringing the threads below the level of the needles as shown in Figs. 4 and 9. Here it is to be observed that if the individual needle *W* is the same in both Figs. 3 and 4, then the individual guide wires *J* and *K* shown in Fig. 4, are different from those shown in Fig. 3, owing to the said lateral displacement of the guide wire carriers.

The sinker carrier *u v* then begins to move away from the frame as the presser 19 is lowered and presses the needles *W*. At this instant the sinker carrier is raised together 50 with the guide wires, (Figs. 5 and 9) but the stitches cannot leave the needles, since the presser 19 presses on the threads and the stitches which have just been formed.

The sinkers are completely disengaged 55 from the threads, and the sinker carrier continues to move away from the frame of the machine. The beards of the needles being kept closed by the presser, the said movement of the sinker carrier knocks over the stitches from the needles, and the presser being raised and the guide wires descending and being shogged in the opposite direction to that which gave the position shown in Figs. 3 and 8, the position shown 60 in Figs. 6 and 9 is reached.

In the movement thus far described, the threads passing through the eyes of the guide wires *J*₁, *J*₂, *J*₃, have been passed over and under the needles *W*₂, *W*₃, *W*₄ respectively, while the threads passing through the eyes of the guide wires *K*₁, *K*₂, *K*₃ have been passed over and under the needles *W*₁, *W*₂, *W*₃ respectively, and a row of stitches has been formed. In the formation of the next row of stitches, the up and down movement of the guide wires and their movements of approaching and receding from the needles takes place exactly as described with reference to Figs. 2 to 11, but the shogging movements of the guide wires at 65 the various phases are in the opposite directions to those described, that is the threads passing through the eyes of the guide wires *J*₁, *J*₂, *J*₃, are passed over and under the needles *W*₁, *W*₂, *W*₃ respectively, while the threads passing through the eyes of the guide wires *K*₁, *K*₂, *K*₃ are passed over and under the needles *W*₂, *W*₃, *W*₄ respectively.

It is to be observed that the travel of the guide wires in their elevating movements, (Figs. 3 and 5) is greater than would be necessary, if it were desired merely to pass the threads over the needles. This is for the purpose of exerting a tension on the threads and pulling them tightly together at the nodes of the fabric, and of feeding a length of the thread to give the desired length of mesh between the nodes.

It is also to be observed that the sinker carriers *u v*, have a movement of considerable amplitude relatively to the machine both vertically and horizontally. These movements are effected by the mechanism hereinafter set forth.

The said tension on the threads and the longitudinal tension applied to the web of fabric as it is formed and wound on the roller, as referred to hereinafter, is of course accompanied by a tension on the threads 100 passing transversely from needle to needle during the formation of the rows of stitches. When the stitches are knocked off from the needles, the transverse tension on the fabric gradually becomes less and less as the rows of stitches move away from the needles. Therefore the width of the web of completed fabric is very considerably less than that at the needles during the formation of the stitches. Accordingly, the fabric is 105 very extensible laterally; it can be stretched to the full width it originally had at the needles without any relative displacement of the threads where they intermesh at the nodes. When the web of fabric is removed from the roller on which it is wound in the machine, and the longitudinal tension is thereby removed, the fabric contracts longitudinally, and can again be stretched to its original length, without relative displace- 110

ment of the threads where they intermesh at the nodes. Thus, the fabric is slightly elastic longitudinally, and highly elastic laterally. This property renders the fabric particularly adaptable for the manufacture of stockings and other underclothing.

Referring now to Figs. 12 and 13, *a* indicates the cam shaft of a machine for rectilinear knitting, on which are keyed the 10 cams *b*, *c*, *d*, *e*, *f*, *g*, *h*, and the driving pulley *i* serving to transmit the various movements. The dipping movements of the guide wire carriers *j* *k* of which the eyes of the guide wires *J* and *K* serve to guide the 15 threads *l*¹ and *m*¹ from the beams *l* and *m*, are effected by means of the cam *e*, which by pressing on a roller *n* causes a lever *o*, pivoted at *o*¹, (Fig. 13) to oscillate.

Near its upper end this lever is connected 20 to an adjustable rod *p*, connected in turn by means of a rod or blade *q*, to a support *r* to which are fastened the carriers *j*, *k*. The return of these latter is effected by the action of the cam *d* on a roller *s*, carried by 25 a lever *t*, pivoted at *t*¹, to the frame of the machine and to the end of which is secured the support *r*. The movement given by the cam *d*, is greater than is usual in knitting machines, and serves not only for the formation of an open mesh, but also for the 30 purpose in combination with the means to be hereinafter described, of producing a stretching of the threads and the formation of a tightened node adapted to prevent ladder- 35 ing in the event of a thread being broken.

The raising of the plates *u*, *v*, which carry the sinkers *x*, is effected by means of the cam *e*, which through the medium of the roller *y* causes the lever *z* to pivot on 40 its axis *z*¹. The horizontal to-and-fro movement of the said plates relatively to the frame of the machine, (Figs. 2 to 6), is effected by means of the cams *f*, *g* (Fig. 12). The first acts through the medium 45 of a roller *2*, on the lever *3* hinged at *4*; the second acts through the roller *5*, on the lever *6*, also hinged at *4*. The levers *3* and *6* are connected together by an arm *7* bent at right angles at its end *8*, and a spring *9* interposed between this bent end and a lug 50 10 of the lever *3*, serves to compensate for the play produced by wear, and ensures the desired quietness of movement of the levers. The transmission of the to-and-fro movement 55 to the plates *u*, *v*, is effected by means of an adjustable rod *11*, of which the heads *12*, *13* are respectively connected to the lever *6*, and to a lug *14* of the plate *u*.

The cams *f* and *g* each have a radially 60 adjustable block *15*, lodged in a recess *16* of the cam. Adjustable bearing screws *17* and clamping screws *18* are provided to fasten the adjustable block in its set position. The said cams come into action when 65 the stitches are about to be knocked off the

needles immediately after the position shown in Fig. 5.

The presser *19* is actuated by the cam *h* which imparts a dipping movement thereto, through the medium of a roller *20*, carried by a lever *21*, hinged at *22*, and of which the other end is secured to the support of the presser. The raising of this latter is effected by a spring *23* hooked at one end, to the end of the lever *21*, and at the other end to a hook *24* of the machine.

Referring now to Fig. 17 which shows the shogging mechanism for effecting the to-and-fro movement of the guide wires in a plane perpendicular to that of the drawing Fig. 2, the plate *j* is fixed on a bar *j*² movable in a slide on the machine; the plate *k* is carried by a similar bar *k*². The bar *j*² is coupled by a double arm *k*³ *k*⁴, to a rod *k*⁵, parallel to the rod *j*⁵ and movable in the same slide. Each of the rods *j*⁵ *k*⁵, carries at its end a roller *j*⁶, *k*⁶, on which a Dawson wheel *j*⁷, *k*⁷, presses. Such a Dawson wheel is described and illustrated on page 46 of part 1 of the English translation of the German book "Technology of Framework Knitting" by Willkomm, translated by Rowlett and published by Kent & Co., London, 1885, the illustrations being given in Fig. 80, and the following figures in the diagrams accompanying such book.

The two discs comprising the Dawson wheel are keyed on the same shaft, which has an intermittent rotary motion imparted to it. On the periphery of each disc steps are cut, the depth of each step corresponding with the distance which separates two consecutive needles *W*, the total depth corresponding to twice this distance. The speed ratios are calculated so that after each turn of the motor shaft of the machine, the shaft which carries the discs turns a fraction of a revolution, such that the peripheries of the discs are displaced for a distance equal to the width of a step. It is to be noticed that to each projection on the disc *j*⁷, there corresponds a recess on the disc *k*⁷ and vice versa. The rollers *j*⁶ and *k*⁶, are maintained pressed against the peripheries of the respective discs by springs *j*⁸ and *k*⁸, hooked to a part 105 fixed to the frame of the machine.

The winding of the fabric is effected on a roller *26*, provided with ratchet teeth *27*, with a stop pawl *28* and a driving pawl *29*. The latter is controlled by a lever *30*, hinged at *31*, and carrying at its end a roller *32*, actuated by the cam *b*.

In known knitting machines, there is provided a lifting device for the roller *26*, arranged in such a manner that it does not exert any pulling effort on the fabric. According to the present invention, on the contrary, a strong pull is exerted on the fabric for the purpose of stretching the threads, and ensuring the tightening of the 125 130

nodes. For this purpose, a ratchet wheel 27, with teeth of small pitch for winding the fabric, is employed.

I claim:

5. 1. A warp knitting machine for making a fabric comprising two sets of threads, in which each individual thread is formed into a series of closed loops, each node is formed by the intermeshing of a plurality of loops 10 of separate threads, and the threads are all pulled tight at the nodes, said machine comprising means for maintaining the fabric under tension and for tightly pulling the nodes of the fabric, and means for giving 15 the yarn guides a greater vertical movement at each stitch than that required merely to pass the threads over the needles for the purpose described.
2. A warp knitting machine for making 20 a fabric comprising two sets of threads in which each individual thread is formed into a series of closed loops, each node is formed by the intermeshing of a plurality of loops of separate threads, and the threads are all 25 pulled tight at the nodes, said fabric being slightly elastic longitudinally, and highly elastic transversely, said machine comprising means for maintaining the fabric under tension and for tightly pulling the nodes of 30 the fabric, and means for giving the yarn guides a greater vertical movement at each stitch than that required merely to pass the threads over the needles for the purpose described.
3. A knitting machine for knitting a warp knitted fabric comprising two sets of threads, in which each individual thread is formed into a series of closed loops, each node is formed by the intermeshing of a plurality of loops of separate threads, and the threads are all pulled tight at the nodes, said machine having means for maintaining the fabric under tension for tightly pulling the nodes of the fabric and means for controlling 40 the to-and-fro movements of the thread feed, said last named means including cams having extensions thereon for giving the yarn guides a greater vertical movement at each stitch than that required merely to pass the threads over the needles.
4. A knitting machine for knitting a warp knitted fabric comprising two sets of threads in which each individual thread is formed

into a series of closed loops, each node is formed by the intermeshing of a plurality 55 of loops of separate threads, and the threads are all pulled tight at the nodes, said machine having means for maintaining the fabric under tension for tightly pulling the nodes of the fabric and means for controlling 60 the to-and-fro movements of the thread feed, said last named means including cams having extensions thereon, said extensions being in the form of adjustable blocks located each in a recess in said cams for giving 65 the yarn guides a greater vertical movement at each stitch than that required merely to pass the threads over the needles.

5. A knitting machine for knitting a warp knitted fabric comprising two sets of threads 70 in which each individual thread is formed into a series of closed loops, each node is formed by the intermeshing of a plurality of loops of separate threads, and the threads are all pulled tight at the nodes, said machine including means for winding the knitted fabric under tension, on a roller operated by a ratchet and pawl device for tightly pulling the nodes of the fabric and means for giving 75 the yarn guides a greater vertical movement at each stitch than that required merely to pass the threads over the needles.

6. In a knitting machine for knitting a warp knitted fabric comprising two sets of threads in which each individual thread is 80 formed into a series of closed loops, each node is formed by the intermeshing of a plurality of loops of separate threads, and the threads are all pulled tight at the nodes, means whereby the sinker carrier plates are 85 given a long longitudinal to-and-fro movement by means of two cams with adjustable blocks, means whereby the yarn guides are given a greater vertical movement at each 90 stitch than that required merely to pass the threads over the needles, and including two other cams, and means whereby the rolling up of the fabric is performed under strong 95 tension, to lengthen the stitches and to pull the threads tightly at the nodes.

In witness whereof, I have hereunto set my hand in presence of two witnesses.

AUGUSTIN SERRA.

Witnesses:

WILLIAM SIMON FRANK RACKHAM,
GRACE PHILLIPS YOUNG.
